UNITED STATES PATENT OFFICE.

CHARLES F. CUNO, OF MERIDEN, CONNECTICUT.

AUTOMATIC SWITCH FOR CIGAR-LIGHTERS, &c.

1,355,943.

Specification of Letters Patent.

Patented Oct. 19, 1920.

Application filed April 22, 1920. Serial No. 375,796.

To all whom it may concern:

Be it known that I, CHARLES F. CUNO, a citizen of the United States of America, residing at Meriden, Connecticut, have invented a new and useful Automatic Switch for Cigar-Lighters, &c., of which the following is a specification.

My invention relates particularly to the type of device known as an automatic cord winding or drum device.

The main object is to provide a simple and inexpensive but reliable mechanism for automatically turning on the current when the drum is rotated a certain amount and a corresponding length of cord has been unwound, and maintaining the current on until all but the same amount of cord is wound up.

In the preferred form of mechanism, one head or disk of the drum or reel has a spiral track, cam, or groove for the circuit closer element and a part of this groove is preferably insulated. In contact with this groove is a circuit closer, so that as the drum is rotated the said closer travels from the insulated to the uninsulated portion of the groove and thus turns on the current. When the drum rotates in the reversed direction, the current is turned off when the contact member reaches the insulated portion of the groove.

Figure 1 is a side view and partial section showing the preferred form of device with the switch "off."

Fig. 2 is a front view and partial section of the cord and current consuming device being omitted.

Fig. 3 is a diagrammatic side view showing the current consuming device and cord drawn out and the switch in the "on" position.

Fig. 4 is an enlarged sectional view showing the method of engagement between the swinging contact member and a grooved disk of the drum.

The casing 5 or housing which may conveniently be of sheet metal supports a stationary shaft 6, on which is mounted a rotatable insulating hub 7. This hub carries a flanged disk 8 within which is mounted the

winding spring 9, which is connected to the drum and a stationary part of the casing or the shaft 6. A spring brush or contact 10 connected to the casing rests on the flange 8.

On the opposite end of the hub 7 is mounted a disk 11, the outer face of which is provided with a spiral groove. The spiral

groove may be formed in any suitable manner as for instance by cutting the groove from solid metal, or by stamping it from sheet metal. A swinging contact member 12 is pivotally supported at 13 and so constructed and arranged as to press toward the disk 11. One end of the spiral groove, in this instance the outer end, is insulated as at 14, whereas the inner end is conductive. This insulation may be effected in any suitable manner, as for instance by coating the outer part of the groove with insulating enamel. The end of the contact member 12 is provided with a tooth or tip 15, which fits into the groove as shown in Fig. 4.

The current consuming device 16 is provided with a flexible cord 17, one wire of which is connected to the disk 8, and thus through the brush 10 to the casing 5 and the binding screw 18, while the other wire is connected to the disk 11, and thus may be connected through the switch arm 12 to the binding screw 19. Any suitable source of current 20 may be employed.

When the parts are in the position shown in Fig. 1, the tip of the contact arm 12 rests in the insulated portion of the groove so that the switch is off and no current flows through the device 16. When the device 16 is pulled out a distance sufficient to rotate the drum until the tip of the contact arm 12 reaches the conducting part of the groove, the current is turned on, and it remains on although the current consuming device may be pulled out to the full length of the cord, and the current will not be turned off until the drum has rotated far enough to bring the tip of the contact arm on to the insulating part of the groove. With the construction as shown in the drawings, the current consuming device will be pulled out several inches before turning on the current, and vice versa when the current consuming device is released, the current will be turned off when the current consuming device is still several inches away from the drum. It will thus be seen that with this construction, the shape and length of the current consuming device has no effect upon the action of the switch. The same switch therefore can be used with different current consuming devices without altering the effect of action in any way, as the switch is entirely independent of the current consuming device. Sometimes in devices of this character the drum fails to wind up all of the cord. With this

invention the current will nevertheless be turned off even though a few inches of the cord is still unwound. The insulating sector of the groove should be sufficiently long to 5 take care of variations in the length of the cord, or variations on winding of the drum. In this construction, the action of the switch is positive at all times, and on account of the sliding character of the action between the 10 tip 15 of the contact arm and the contact groove, the contact surfaces are kept polished, bright and clean.

I claim:

1. In an automatic switch, a disk having 15 a spiral cam rotatable therewith and having an insulating portion, and a switch member having a projection traveling on said cam of said disk, a current consuming device, a conducting cord connected to said device and 20 wound on said drum.

2. An automatic switch comprising a cord carrying drum, a spiral cam member rotatable therewith and having an insulated portion and a conducting portion, and a contact 25 co-acting with said cam and operated to make and break contact with said conducting portion as the cord is unwound and wound respectively but independently of the cord.

3. In an automatic switch, a winding drum having a spirally grooved contact portion, and a movable contact arm having a tooth traveling in the groove of said contact portion and movable thereby to make and break 35 a circuit.

4. An automatic switch comprising a cord winding drum, a contact member driven by the rotation of said drum and having a spiral cam, and a contact member slidably 40 engaging said cam for turning on the current after a predetermined rotation of the drum has taken place, and turning off the current when the drum returns to a predetermined position.

5. An automatic switch, comprising a spring driven winding drum for a cord, a make and break contact member carried by 45 said drum and having a conducting portion and an insulating portion, and a contact member normally in contact with the insulating portion of said contact member for opening the circuit when the drum is in its position of rest.

6. An automatic switch, comprising a 55 spring driven winding drum for a cord, a contact member connected to move with said drum and having a conducting portion and an insulating portion, and a contact piece carried by said contact member and nor-

said contact member for turning off the current when the drum is in its normal position and for turning on the current after a predetermined rotation of said drum.

7. An automatic switch for cigar lighters, etc., comprising a drum, a spiral cam rotatable thereby, and a movable switch member engaging said cam and moved by said cam to make and break a circuit when said drum has been rotated a given distance 70 in one direction or the other.

8. An automatic switch for cigar lighters, etc., comprising a drum, a spiral cam rotatable thereby, and a movable switch member engaging said cam and moved by said 75 cam to make and break a circuit when said drum has been rotated a given distance in one direction or the other, said cam being carried on one end of said drum.

9. In an automatic switch for cigar lighters, etc., a rotatable drum, a spiral cam mounted on one end of said drum, a portion of said cam being adapted to carry current, another portion being insulated, and a movable switch member in contact with said 85 cam and moved thereby, that part of said switch member engaging said cam being suitable to carry current whereby a circuit may be opened and closed through said cam and switch member depending upon 90 what part of the cam is in contact with said switch member.

10. An automatic switch for cigar lighters, etc., comprising a drum, a spiral cam rotatably mounted upon the end of 95 the drum, and a circuit making and breaking device in contact with said cam for movement thereby, a portion of said cam being insulated whereby when said circuit making and breaking device is in contact 100 with one part of the cam the circuit will be closed, and when in contact with another part of said cam said circuit will be open.

11. In an automatic switch, a rotatable disk having a spiral groove, a portion of 105 said groove being of conducting material, and another portion of non-conducting material, and a movable contact member having a portion projecting into said groove to be moved thereby as the disk rotates for 110 making and breaking a circuit.

12. In an automatic switch for cigar lighters, etc., a rotatable drum, a spiral cam rotatable thereby, a movable member engaging said cam and moved thereby, the 115 circuit being broken when said movable member is in one position and being closed when said movable member is in another position.

CHARLES F. CUNO.
